UNITED STATES PATENT OFFICE

JOHN J. FOGARTY, OF PHILADELPHIA, PENNSYLVANIA, ASSIGNOR TO JENKINS INTER-LOCK MANUFACTURING COMPANY, OF PHILADELPHIA, PENNSYLVANIA, A CORPORATION OF PENNSYLVANIA

ELEVATOR CONTROL

Application filed November 6, 1931. Serial No. 573,372.

This invention relates to an elevator control, more particularly to means whereby the operation of an electrically driven elevator will be definitely prevented in case any 5 of the doors giving access to the shaft, as at landings, are open, and whereby a door cannot be opened unless the elevator is in stopped position adjacent the corresponding landing.

Specifically the invention relates to that 10 type of control illustrated in the patent to Holberg, Patent No. 1,536,343 and in my prior application, Ser. No. 447,135, filed April 25, 1930.

It is the broad object of the present invention 15 to provide an improved arrangement of the general type indicated above, which is of simple construction and which will be noiseless in operation. More particularly the present arrangement overcomes certain 20 undesirable features of the arrangement illustrated in the Holberg patent. For example, in hospitals it is desirable to have the operation as quiet as possible. If a solenoid such as that used to break the toggle in the 25 Holberg arrangement, is energized by alternating current, it sometimes happens that a continuous hum at the frequency of the alternating current will occur, which may be amplified and made quite noticeable by the 30 metallic parts of the car. Furthermore, the toggle arrangement may possibly stick in which case, even though the solenoid is de- 35 energized, it may not straighten out in the proper fashion.

Attainment of the objects of improving the prior arrangements will become apparent 40 from the following description read in conjunction with the accompanying drawing in 45 which the figure is a vertical section showing the relationship of the parts of the apparatus carried by a car to portions of the apparatus located at the landing and controlled by and 50 controlling the landing gate.

In the drawing there is illustrated a typical 55 installation of an embodiment of the invention at a single landing, it being understood that similar installations are made at each landing. Further, while the arrangement is 60 illustrated in connection with a sliding gate,

it is equally applicable to any other type of gate or door.

The floor of a car is indicated at 2 carrying a plate 4 on which is secured the inter-lock assembly. This inter-lock assembly includes 55 the car shoe 6 arranged to co-operate with a shoe 7 pivoted on a vertical axis to the wall of a shaft below a landing. This last mentioned shoe is arranged to control and be moved by the usual rotating cam 9 which is 60 provided with a notch within which engages a bar 11 extending downwardly from the gate.

The car shoe 6, which corresponds to the 65 one illustrated in the Holberg patent, as connected to the toggle, is carried by a plunger 8 slideable within a fixed cylinder 10 carried by a suitable bracket 12. A slot 14 in the wall of the cylinder 10 receives a pin 16 carried by the plunger 8 to prevent rotation of the 70 plunger about its axis. A spring 18, reacting between the end of the cylinder 10 and the plunger 8, normally urges the car shoe 6 outwardly to a position to engage the shoe 7 located at the landings. 75

An extension 20 of the plunger 8 carries 80 a rack 22 meshing with a pinion 24 secured to the shaft of the torque motor 26, the rack 22 being held in mesh with the pinion 24 by a downwardly extending pin 27 carried by the plate 4.

The torque motor is of a type now generally available for operation by commercial alternating current. This motor has the characteristic of being capable of holding a load 85 in stationary position for an extended period of time without danger of over-heating and also quietly without the hum usually attending a stationary, alternating current motor or electro-magnet. In the present instance the motor is designed, when energized, to draw the plunger 8 inwardly against the tension of the spring 18 to such an extent that the car shoe 6 will clear the shoe 7 during the running of the elevator. The motor 26 is energized whenever the driving power is applied to the elevator. Accordingly, the car shoe 6 will move outwardly against a shoe 7 to permit opening of the corresponding gate only 95 when the power is cut off from the elevator. 100

In this way there is accomplished the same result as indicated in the Holberg patent; i. e. in the case of an automatic elevator which, as it passes a landing, cannot be stopped by opening a door at any landing except that to which it is called.

To secure silent and smooth operation of the device the car shoe 6 is connected by a link 30 to a piston 32 located within a cylinder 10 34 which is vented to the atmosphere through an opening controlled by a screw 36 which adjusts the effective area of the opening so as to control the flow of air therethrough and accordingly the speed of movement of the 15 piston 32 under the action of either the spring 18 or the torque motor 26.

The rubber cushion 28 is provided to prevent sound as the shoe moves to its limiting outward position.

20 The operation of the device has already been indicated by the above described direct operation of the car shoe by the torque motor. Herein is provided an arrangement which is silent in operation and which by reason of 25 its simplicity will not get out of order.

What I claim and desire to protect by Letters Patent is:

In an interlocking device for automatically controlled electric elevators in combination with a shaft provided with a landing and a gate therefor, and an elevator car, a shoe at the landing, connections whereby said shoe controls the gate, a shoe on the car adapted to engage the landing shoe, and means for controlling the position of the car shoe, said means including a torque motor, a pinion driven by the motor, a rack meshing with the pinion and connected to the car shoe whereby the motor moves the car shoe in one direction, a spring for moving the car shoe in the opposite direction, and a dash pot for controlling movements of the car shoe, said dashpot comprising a fixed cylinder having a restricted outlet, and a piston movable in the cylinder and connected to the car shoe.

In testimony of which invention, I have hereunto set my hand, at Philadelphia, Pa., on this 4th day of November, 1931.

JOHN J. FOGARTY.
